SNELED HOOK CASE

William J. De Witt and Paul A. Ross, Auburn,
N. Y., assignors to Shoe Form Co., Inc., Auburn,
N. Y., a corporation of New York

Application February 19, 1937, Serial No. 126,610

7 Claims. (Cl. 43—32)

This invention relates to an improvement in fishing hook cases and more particularly in cases for snelled hooks.

The object of this invention is to provide a case so constructed that the snells are held perfectly straight and ready for use whereby injury due to bending or coiling the snells is prevented and the life of snelled hooks is prolonged.

This and other objects will appear from a consideration of the following description and of the accompanying drawing which forms a part thereof and in which

Fig. 1 is a perspective view of a case embodying this invention, shown open;

Fig. 2 is a sectional view on an enlarged scale of a portion of a closed case the section being taken longitudinally, substantially along the line 2—2 in Fig. 1; and

Fig. 3 is an enlarged cross sectional view of a closed case.

The case 10 comprises a base plate 11 and a cover plate 12, joined by hinges 13. The base plate comprises flat end and central portions 15, 16 and 17 and longitudinally grooved portions 18 and 19. The base of each of portions 18 and 19 is provided with a plurality of parallel longitudinal arcuate depressions 20 forming spaced grooves (see Fig. 3).

Fastened upon each end portion 15 and 16 is a transversely extending rack 21 secured at its ends to an end portion and spaced therefrom intermediate its ends. A plurality of notches 22 are formed in the outer edge of each rack adapted to receive and hold hooks. Mounted transversely on the central portion 17 is a coil spring 23 secured in position by a wire 24 passed longitudinally therethrough.

The cover plate 12 comprises end portions 25, 26, a central portion 27 and intermediate longitudinally grooved portions 28 and 29. The end and central portions are transversely curved as shown in Fig. 2 to form chambers which, when the case is closed, receive the racks 21 and spring 23. The tips 30 of the end portions are flared outwardly so that when the case is closed they have a substantial surface contact with the end portions 15 and 16 of the base plate. In the base of each of the intermediate portions are provided parallel longitudinally extending depressions 31 forming spaced grooves. The depressions 20 in the portions 18 and 19 of the base plate are in alignment as are the depressions 31 in the portions 28 and 29 of the cover plate and both sets are so located that they register when the case is closed to form chambers each adapted to receive a snell. Suit-

able means are provided for locking the case closed as for example the U-shaped clips 33 pivoted on the base plate which clamp the edges of the plates together (see Fig. 3).

The snelled hooks are placed on the base plate 5 of the case with the hooks in the notches of the racks 21 and the snells lying in the depressions 20 and held therein by being forced between coils of the spring 23. Upon closing the case the depressions 31 in the cover plate register with the 10 depressions 20 to form closed chambers (Fig. 3) in which the snells are contained. Thus they are prevented from bending or coiling and are ready for use at any time.

While one embodiment of this invention has 15 been shown and described it will be understood that the invention is not limited thereto and that other embodiments may be made without departing from the spirit and scope thereof as set forth in the following claims.

We claim:

1. A snelled hook case comprising a base plate having a rack at one end provided with hook receiving notches, longitudinally extending depressions adapted to receive the snells and snell engaging means for holding them in the depressions, and a cover plate therefor, said cover plate having longitudinally extending depressions which, when the case is closed, register with the depressions in the base plate and form therewith 20 closed snell containing chambers.

2. A snelled hook case comprising a base plate having a rack at one end provided with hook receiving notches, longitudinally extending depressions adapted to receive the snells, and separated 25 into two groups and a coiled spring fastened to the base plate in the space between the groups between the coils of which spring the snells are passed to hold them in the depressions and a cover plate therefor.

3. A snelled hook case comprising a base plate having a rack at one end provided with hook receiving notches, longitudinally extending depressions adapted to receive the snells, and separated 45 into two groups and a coiled spring fastened to the base plate between the coils of which the snells are passed to hold them in the depressions and a cover plate therefor, said cover plate having longitudinally extended depressions, which are arranged in groups, as are the depressions in the 50 base plate, and register therewith when the case is closed.

4. A snelled hook case comprising a base plate having a rack at one end provided with hook receiving notches, longitudinally extending depre- 55

sions adapted to receive the snells, and separated into two groups and a coiled spring fastened to the base plate between the coils of which the snells are passed to hold them 5 in the depressions and a cover plate therefor, said cover plate having longitudinally extended depressions, which are arranged in groups, as are the depressions in the base plate, and register therewith when the case is closed, and a curved 10 portion intermediate the groups of depressions which covers said coiled spring when the case is closed.

5. A snelled hook case comprising a base plate having at each end transversely extending racks 15 provided with hook receiving notches, at the center a transversely extending coiled spring and between the spring and each rack a plurality of longitudinally extending depressions adapted to receive the snells with a portion between the coils 20 of the spring and a cover plate having at each end and at the center transversely extending curved portions and between such portions a plurality of longitudinally extending depressions, said cover 25 plate depressions registering with the base plate depressions and the curved portions of the cover

plate covering the racks and spring when the case is closed.

6. A snelled hook case comprising a plate having at each end a rack provided with hook receiving notches, said racks being parallel, a coiled 5 spring carried by the plate, between the racks and parallel thereto adapted to hold straight the snells attached to hooks in the notches of the racks, depressions formed in said plate between the spring and each rack adapted to receive such 10 snells and a cover.

7. A snelled hook case comprising a plate having at each end a rack provided with hook receiving notches, said racks being paralleled, a coiled spring carried by the plate, between the 15 racks and parallel thereto adapted to hold straight the snells attached to hooks in the notches of the racks, depressions formed in said plate between the spring and each rack adapted to receive such snells, and a cover said cover having 20 chambers in the end portions thereof which receive said racks to prevent inadvertent contacts with the hooks.

WILLIAM J. DE WITT.

PAUL A. ROSS.
